UNITED STATES PATENT OFFICE.

CHARLES L. PEIRCE, JR., OF PITTSBURGH, PENNSYLVANIA, ASSIGNOR OF ONE-HALF TO HUBBARD & COMPANY, A CORPORATION OF PENNSYLVANIA.

INSULATOR SUPPORT OR BRACKET.

Application filed February 23, 1918. Serial No. 218,802.

To all whom it may concern:

Be it known that I, CHARLES L. PEIRCE, Jr., a citizen of the United States, and a resident of Pittsburgh, in the county of 5 Allegheny and State of Pennsylvania, have made a new and useful Invention in Insulator Supports or Brackets, of which the following is a specification.

This invention relates to insulators and 10 brackets for rigidly supporting the same and the objects thereof are to provide an insulator and support by means of which wires may be attached to buildings without the use of tie wires; an insulator having 15 relatively large leakage distance and good drainage; an insulator and metal support for the same in which the strains to which the support is subjected are practically only tension strains and those to which the insulator 20 is subjected are practically only compression strains; a support which will allow broken insulators to be replaced without removing the support from the building to which it is attached; an insulator and 25 support which may be fastened in any desired position on a building without impairment of the insulation; a combined insulator and support for use on buildings in which the insulator has a wire receiving 30 hole through which the wire may be strung and slidably retained without the use of tie wires or equivalent fastening means.

A further object is to provide an insulator and supporting bracket therefor which 35 will be cheap to manufacture and which will have great strength, stability and general efficiency.

These as well as other objects which will readily appear to those skilled in this art, 40 I attain in the device shown in the drawings accompanying and forming a part of this application and in which Figure 1 is a view partially in plan and partially in section of a device embodying this invention, the sectional portion being taken on line 1—1 of Fig. 2; Fig. 2 is a view partially in side elevation and partially in sectional elevation of the device, the sectional portion being taken on line 2—2 of Fig. 1, 45 and Fig. 3 is a view in cross section taken on line 3—3 of Fig. 1.

The supporting bracket consists of a back piece 4 made up from a narrow channel section of iron or steel and to the flat face 50 of this channel section substantially U

shaped supports or insulator jaws 5 and 5^a are rigidly applied. These jaws or supports are bent up from strap metal preferably having the same width as the back piece. To provide secure seats for the fixture, straps 60 6 are applied over the central portion 7 of each U shaped member. These straps are pressed from sheet metal and each has the central body portion 8 of arched shape for saddling over the central portion of the U 65 shaped member between the support arms, and wings or feet 9 and 9^a extend laterally from the body of the strap to provide seats for the fixture. The seats have bolt holes extending therethrough by means of which 70 the bracket may be secured to a supporting element such as the side of a building. Each strap is secured in place by the same rivet 75 11 which holds a U shaped member to the back piece. In other words a single rivet passes through the strap, U shaped member and back piece as clearly shown in Figs. 2 and 3. The bends 12 and 13 between the wings and body of the strap are rounded and to add strength longitudinally extending corrugations 14 are formed in the bends. 80

The insulating members 15 are preferably made of porcelain and being formed to provide relatively large leakage distance and good drainage are inserted within the 85 U shaped member and held rigidly in place by arms 5, 5^a which are spaced apart so as to snugly fit the insulators. A retaining bolt 16 passes through a hole 17 formed in the insulator for that purpose and holes 90 18, 18^a, in the jaws 5 and 5^a. Each insulator is provided with a wire receiving eye or passage 20 which passes through the insulator back of the supporting bolt 19 or rather between the supporting bolt and 95 body portion 4 of the support bracket. The insulator shown in the drawings is provided with a support arm receiving groove in each lateral end face, which extends outwardly from the base of the insulator toward the outer end thereof. Each groove, however, terminates in a shoulder near the outer end of the support. With this arrangement, the grooves co-act with the arms 5 and 5^a to ensure a proper positioning of 100 the insulator on the support. The aperture 17 terminates in these grooves.

Having thus described my invention what I claim is—

1. The combination with an insulator sup- 110

- port having outwardly projecting arms, of an insulator straddled by said arms and having an arm receiving groove formed in each lateral face thereof, a wire receiving 5 aperture extending therethrough intermediate said faces, a peripheral groove extending partially around the insulator and terminating at each end in said wire receiving aperture and a bolt receiving aperture terminating 10 in said arm receiving grooves, and a bolt extending through said bolt receiving aperture and through registering apertures formed in said arms.
2. The combination with an insulator support having outwardly projecting arms, of an insulator movable longitudinally to position between said arms and having a wire receiving aperture formed therein intermediate the arm engaging sides thereof, a bolt receiving aperture extending at right angles to the wire receiving aperture and located between said wire receiving aperture and the outer end of the insulator and a bolt extending through said bolt receiving aperture and through apertures formed in said arms. 15
3. The combination with an insulator support having a U-shaped member forming 20
- outwardly projecting arms, of an insulator located between and projecting laterally beyond said arms and having a wire receiving aperture extending therethrough between the faces thereof adjacent said arms and a bolt receiving aperture extending therethrough at right angles to the wire receiving 25 aperture and a bolt extending through said bolt receiving aperture and through registering apertures formed in said arms.
4. The combination with an insulator support provided with parallel outwardly projecting arms having bolt receiving apertures adjacent the ends thereof, of an insulator located between said arms and having an arm receiving groove formed in opposite side faces thereof, a wire receiving aperture 30 extending therethrough between said arms and a bolt receiving aperture extending therethrough beyond said wire receiving aperture and registering with the apertures in said arms and a bolt extending through 35 the apertures in said arms and said bolt receiving aperture in the insulator.

In testimony whereof, I have hereunto subscribed my name this nineteenth day of February, 1918.

CHARLES L. PEIRCE, JR.
